CLAIM

The ornamental design for a tripod, as shown and described.

DESCRIPTION

FIG. 1 is a perspective view of a tripod showing my design;

FIG. 2 is another perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a perspective view of another embodiment of my new design of FIG. 1;

FIG. 8 is another perspective view thereof;

FIG. 9 is a front elevational view thereof;

FIG. 10 is a rear elevational view thereof;

FIG. 11 is a right side elevational view thereof; and

FIG. 12 is a left side elevational view thereof.
